CONTAINER STRUCTURES

Woodrow S. Wilson, Pasadena, Morton A. Carabel, Los Angeles, and Dell M. Malick, Whittier, Calif., assignors to Poleete, Inc., Los Angeles, Calif., a corporation of California

Application December 27, 1955, Serial No. 555,491

2 Claims. (Cl. 222—534)

The present invention relates to new and improved container structures.

The advent of resilient plastic materials such as, e. g., various grades of polyethylene, polyvinyl chloride, polyvinyl acetate, and other similar substances, has given rise to a great change in the art of packaging materials such as cosmetics, shampoos and the like. Virtually every individual is, at the present time, familiar with the so-called "squeeze bottle" containers formed of these materials and used for a number of preparations. Such containers of a resilient plastic are very satisfactory for a large number of applications in that they are substantially unbreakable, and hence may be employed with safety where children are apt to be involved or where these containers are apt to be damaged due to dropping or the like.

Unfortunately, the art of dispensing various liquid or semi-liquid preparations from containers has not kept pace with progress in the art of manufacturing containers from resilient plastic materials. A basic object of this invention is to provide new structures for dispensing liquids from containers, these structures being specifically adapted to be utilized with resilient plastic containers of the type indicated in the preceding discussion.

Another object of this invention is to provide container structures formed out of a resilient plastic which mark a substantial improvement over various prior devices in that they incorporate a spout which is designed to lie substantially flush with a surface when not in use. This latter is very important since spouts which project upwards from a lid or the like are located in an exposed position where they are apt to be damaged in handling. Also, the prior spout constructions projecting away from a lid are very disadvantageous in that they occupy considerable volume when packed and shipped. Further, these prior constructions are also virtually impossible to utilize with containers which are specifically adapted to be nested together for display and shipping purposes.

Because of the nature of this invention, it is not believed necessary to set forth in this specification a long list of objects pointing out all of the advantages and details of the structures falling within the scope of this disclosure. Other advantages and objects of the invention will be more fully apparent to those skilled in the art to which this invention pertains from a consideration of the remainder of this description, including the appended claims and the accompanying drawing, in which:

Fig. 1 is a perspective view of a container of the present invention, this view illustrating the bottom of the container;

Fig. 2 is a cross sectional view taken at line 2—2 of Fig. 1;

Fig. 3 is a cross sectional view taken at line 3—3 of Fig. 2;

Fig. 4 is a cross sectional view taken at line 4—4 of Fig. 3;

Fig. 5 is a bottom view of part of the container shown in Fig. 1;

Fig. 6a and Fig. 6b are detailed sectional views indicat-

2

ing the formation and final structure of the container shown in Fig. 1;

Fig. 7 is a cross sectional view of a modified structure of the present invention;

Fig. 8 is a cross sectional view taken at line 8—8 of Fig. 7; and

Fig. 9 is a cross sectional view similar to Fig. 7 of a second modified structure of the present invention.

In all figures of the drawing, like numerals are used to 10 designate like parts wherever convenient for purposes of illustration and explanation. It is to be understood that this invention is not limited to structures having the precise appearance and dimensions shown inasmuch as the basic features of this invention can be embodied within other structures having a completely different general appearance.

The invention present in this specification is considered 15 to be fully defined or summarized by the appended claims. If desired, however, it may be stated by way of a summary

20 which will aid in the understanding of this description that the present invention concerns containers which include: elongated, closely spaced side walls connected together by curved ends, these walls being formed of a resilient material; a bottom located within the confines of the side 25 walls so as to be spaced from the lower edges of these side walls; and means for dispensing the contents of a container attached to this bottom. The invention is best explained in detail by referring directly to the drawings.

In Fig. 1 of the drawings there is shown a complete 30 container 10 of the present invention, formed almost completely out of a resilient plastic material such as, e. g., polyethylene. This container includes a flat top 12, opposed elongated side walls 14 which are connected together by curved ends 16, and a bottom 18, this bottom being 35 located against an internal flange 20 formed on the inside of the container. Around the periphery of the top 12 there is formed a groove 22 which is adapted to carry the lower edge 24 of the side walls 14 of an adjacent container. It should be noted that the flange 20 is spaced 40 from the lower edge 24 of the container 10 a sufficient distance so that the bottom 18 is within the confines of the side walls 14.

One major advantage of the container 10 lies in the 45 ease with which this container may be filled with a liquid by either hand or automatic means as it is being assembled. During such filling, the container 10 with the bottom removed is placed upside down upon a horizontal surface so that the top 12 rests upon this surface. A fluid, such as hand cream, shampoo or the like, is then placed within 50 the container below the level of the flange 20. Next a continuous wire 26 formed of stainless steel or other similar material which is not apt to be corroded or attacked by the contents of the container 10, and which is not apt to contaminate in any respect the contents of this 55 container, is placed against the flange 20. It should be noted that the wire 26 fits closely against the inside of the container 10. Next, the bottom 18 is merely dropped in place upon the wire 26 and upon the flange 20. At this stage during the assembly of the container 10, the 60 flange 20, the bottom 18 and the wire 26 are located with respect to one another as indicated in Fig. 6a of the drawings.

Next, this assembly, including the fluid within the container 10, is passed through an induction heating coil 65 of conventional design which induces a current within the wire 26 so as to cause this wire to heat very rapidly. This, in turn, has the effect of melting the plastic material adjacent to the wire in the flange 20 and the bottom 18 and, to a certain extent, on the inside of this container. 70 As such melting occurs, the plastic from these various parts flow together so that as the container 10 is removed from the induction coil the wire 26 is in effect

embedded in composite unitary structure in the manner shown in Fig. 6b. It is frequently advantageous to apply moderate pressure to the bottom 18 during this heating operation in order to aid in the forming of a seal between the parts. Inasmuch as occasionally the wire 26 may not be completely encased within plastic, it is preferred that this wire have the properties indicated above with respect to the contents of the container. In addition to serving as an aid to sealing the container 10 the wire 26 serves to reinforce part of this container so as to prevent bending of the side walls 14 which would tend to break the seal between the flange 20 and the bottom 18.

If desired, a spout member 28, which may be formed of a plastic as indicated above, having a cylindrical center section 30, a spout 32 projecting radially from this center section, and cylindrical projections 34 leading axially from both sides of the center section 30 may then be inserted in an operative position within the bottom 18. This bottom is formed so as to include a generally cylindrical cavity 36 having a flat bottom 38 and an opening 40 leading from this cavity 36 to the outside of the bottom 18; cylindrical bearing openings 42 project axially from the cavity 36 within the bottom 18. Further, this bottom 18 is formed so as to include a groove 44 leading from the cylindrical cavity 36 to an enlarged depression 46 within this bottom. The structure of the bottom immediately adjacent to the cylindrical cavity 36 and the bearing openings 42 is quite important with this invention.

Aligned slots 48 are provided in the bottom 18 along the length of the bearing openings 42 so that the spout member 28 may be snapped into the position shown in Figures 2, 3, 4 and 6 of the drawings with the cylindrical projections 34 being held tightly within the bearing openings 42 by the portions of the bottom 18 defining these bearing openings. When this is done, the cylindrical center section 30 is located within the cylindrical cavity 36 and is held against the bottom 18 so as to tend to deform this bottom to a cylindrical shape effecting a tight seal between the cylindrical center section 30 and the bottom 18 around a passage 50 leading through the bottom 18 from the interior of the container 10 to within the center of the flat bottom 38.

It will be realized by those familiar to the field to which this invention pertains that the size of the seal obtained with this structure is comparatively small but that nevertheless it is adequate. Because of the size of the area forming a seal there is little danger of leakage resulting from imperfect moulding of cylindrical surfaces or the like. Another passage 52 is formed in the spout member 28 so as to project completely through the spout 32 and the cylindrical center section 30 so that when the spout member is rotated to the position shown in phantom in Figures 2 and 3 of the drawings these two passages 50 and 52 are aligned with one another. The seal referred to above is, of course, maintained during this rotation.

It is considered obvious that when the spout member 28 is in this position that the contents of the container 10 may be readily removed from this container. One important feature of the preferred construction of this invention shown in Figures 1 and 2 of the drawings lies in the fact that the side walls 14 are elongated and are spaced comparatively closely to one another in such a manner that the container 10 may be readily held within the hand of an individual so that these two side walls 14 may be squeezed towards one another, ejecting the contents of the container under force through the passages 50 and 52. The amount of deformation of the side walls 14 possible is comparatively large with the structure illustrated inasmuch as these side walls are substantially unsupported throughout their length by any means which would tend to prevent them being moved towards one another. Because of the structure shown the container 10 is quite advantageously used with hand creams or sham-

poo since the contents of the container are ejected from the bottom of it during use directly towards the hands or the head or the like as desired without the necessity of tilting up this container or holding it in some peculiar position.

The spout member 28 is normally carried in the position shown in Figs. 2, 3 and 5 of the drawings with the spout 32 within the groove 44 so as to project into the depression 46. It is considered obvious that when in this position the passages 50 and 52 are not aligned with one another and that the spout 32 is in a location which in effect is "out of the way" where it cannot be damaged in handling and where it does not interfere with stacking or shipping operations. The depression 46 is larger than the spout 32 with the preferred construction in order that a finger may be readily inserted within the depression 46 to flip the spout 32 to a position where the passages 50 and 52 are aligned with one another. An end 54 of the opening 40 serves as a stop element to limit rotation of the spout member 28 to where these two passages are in alignment. As the container 10 is placed upon a flat surface the spout member 28 is automatically closed, or rotated to a closed position. This is an important advantage, as is the fact that the container 10 may be dropped into water or the like during use.

It is not to be assumed from the foregoing that the spout member should be inserted in an operative position after the bottom 18 has been attached to the rest of the container 10. It is considered preferable for commercial reasons to insert the spout member 28 in the bottom 18 prior to the attachment of this bottom to the rest of the container in a sub-assembly type of operation. It is also not to be assumed that the container 10 must be filled as this container is being assembled as it is possible to fill the container through the passages 50 and 52, although this is not preferred. It is also possible to utilize various other openings (not shown) to fill the container 10.

The basic features of the spout structure of this invention can be employed with a cap 60 as shown in Figs. 7 and 8 of the drawings. This cap is designed to be attached by internal threads 62 to a bottle or other similar structure, and employs at its top 64 a spout member 28' of identical construction with the spout member previously described. It also utilizes a cylindrical cavity 36' and other openings and slots such as have been indicated. With this structure the spout 32' projects through a groove 44' a short distance beyond the periphery of the cap 60 so that it may be easily engaged and flipped to an open position. In spite of this the spout 32' is located in a manner where this spout does not project from the cap 60 to any material extent.

It is also possible to utilize the same spout and retaining structure in another cap 66 of the instant invention having external threads 68. This cap 66 is designed to be threaded within an opening 70 in the top 72 of a container so that the spout member 28" is completely disposed in a closed position beneath the surface of the top 72 for convenience in stacking and in order to prevent damage in handling and the like. The structure employed in the modification of the invention shown in Fig. 9 of the drawings is identical to that employed together with the bottom 18 of the container 10, and hence it will not be described in detail.

Because of the fact that the basic features of this invention can be utilized in a number of modified structures, the present inventive concept is to be considered as being limited only by the appended claims.

We claim:

1. A container of the class described which comprises: elongated, closely spaced side walls connected together by curved ends, said walls being formed of a resilient material; a bottom located within the confines of said walls so as to be spaced from the lower edges thereof; means for dispensing the contents of a container attached to said bottom, said means including a rotatable member adapted

to rotate so as to be held against said bottom when in a closed position and so as to extend from said bottom when in an open position.

2. A container as defined in claim 1 including flange means formed on the interior of the said side walls; a metal member located adjacent to said flange, said bottom being located against said flange and said metal member, said flange and said bottom being fused to one another.
